UNITED STATES PATENT OFFICE.

JOSEPH F. MUSSelman, OF BRONXVILLE, NEW YORK, ASSIGNOR, BY MESNE ASSIGNMENTS, TO ELLIOTT COMPANY, OF PITTSBURGH, PENNSYLVANIA, A CORPORATION OF PENNSYLVANIA.

SYSTEM FOR RENDERING LIQUIDS NONCORROSION.

Application filed March 27, 1920. Serial No. 369,364.

To all whom it may concern:

Be it known that JOSEPH F. MUSSelman, a citizen of the United States, residing at Bronxville, Westchester County, New York, has invented certain new and useful Improvements in a System for Rendering Liquids Noncorrosive, of which the following is a specification.

This invention relates to a system for rendering water or other liquids non-corrosive by the removal of the dissolved oxygen and other corrosive gases or materials therefrom, thus rendering it corrosively inactive.

The object of this invention is to provide a simple, practical and efficient system in which the active corrosive agents are more or less—and for all practical purposes—completely removed from the liquid without raising the temperature of the same to the boiling point.

The invention consists in the novel arrangement and construction of the apparatus, as will appear more fully hereinafter in connection with the description of the illustrative embodiment of the same shown in the accompanying drawings and particularly defined in the claims.

In the drawings I have shown, in conventional diagrammatic form, a typical arrangement or adaptation of my invention to the hot water system of a building, the object being to prevent corrosion in the system of pipes through which the water is delivered to the several parts of the building and also in the boiler or other heating means for heating the water supply.

The usual hot water system for a building is indicated by the tank 1, usually located on the roof, from which the water is supplied through the pipe line 2—3 to the heating tanks or boilers 4—4, from which the several floors are supplied through the pipe 5 and risers 6, 7, and 8. The return pipe 9 carries the circulation and surplus water back to the boilers or heating tanks 4—4.

The water thus supplied in the ordinary manner carries corrosive gases dissolved therein, such as free oxygen and other free gases, such as carbonic acid gas and nitrogen, which especially when the water is heated and in motion, are very active corrosive agents which destroy the pipes and boiler and also produce "gas pockets" and "slugs" in a closed hot water system, with

resulting interference with the flow and circulation.

To accomplish the removal of these gases and other results, I provide a by-pass valve 10 in the supply line 2—3 which, when closed, causes the water to flow from the supply line 2 through a pipe 11, which may be provided with a valve 12, through a coil 13 in an auxiliary heater 14, from which it passes through a pipe 15, which may be provided with branches 16 and 17, to the interior of a tank or container 18, which tank is known as a "de-aerator." From this de-aerating tank the water passes through pipes 19 and 20, the latter being provided with a valve 21, to the supply line 3, on the opposite side of the by-pass valve 10, and thence through the hot water system hereinbefore described. The de-aerating tank 18 is preferably located at a point sufficiently above the hot water system of pipes to the several floors to insure the flow of the water thereto without the use of a pump.

The auxiliary heater 14, as shown, comprises an outer shell or casing which encloses the coil 13 and to which hot water or steam may be supplied and returned or circulated through the pipes 22 and 23, controlled by a thermostatic valve 24; or other suitable heating means may be used adapted to heat the water passing into the de-aerating tank 18 to a predetermined temperature a few degrees below the boiling point.

The de-aerating tank 18 is equipped with a series of pans 25 positioned under the interior or discharge ends of the branch pipes 16 and 17. These pans are arranged to produce a "cascade" effect as the water overflows from one to the other, or a series of sprays may be used, either in connection with or instead of the pans, the object being to agitate and separate the water into small particles and thus cause the corrosive and other gases to be given off readily.

A float 26 in the tank 18 is operatively connected by means of a lever 27 and link 28 to a valve 29 in the supply pipe 15 and serves to regulate the level of the water in the tank 18.

A vacuum pipe line 30 communicates with the upper part of the tank 18 above the water level for producing a partial vacuum therein and drawing off the gases given off from the water by means of any suitable

vacuum producing apparatus, such as a fluid operated ejector or water jet vacuum pump 31, which may be operated in the usual manner by water supplied through the pipe 32 and valve 33 connected with the supply line 2-11.

A gauge 34 and vacuum breaker 35 may be connected in the vacuum line 30 to relieve the vacuum in the tank 18 when desired and also a thermostatic trap 36 may be connected in said line to regulate the vacuum according to the temperature of the gases and air drawn out from the tank 18. The construction and operation of these several devices is well understood and need not be explained in detail here, as the same are the usual commercial apparatus made and sold for this purpose.

I have found by a number of experiments 20 with my system that in order to insure the de-aeration or driving off of substantially all of the active corrosive and other gases from the water it is only necessary to raise the temperature of the same to a point a few degrees under the boiling point corresponding to the pressure to which it is subjected and by creating a partial vacuum in the de-aerating tank 18 the de-aeration takes place at a still lower temperature, as 30 the boiling point is lowered, and by regulating the vacuum this operative or working temperature can be lowered, within certain limits, to any desired point, resulting in a greater economy in the operation of the auxiliary heating means 13-14 and also 35 permitting the use of a heating means of less capacity without reducing the efficiency of the system.

In some cases it may be desirable to operate 40 the de-aerating tank 18 at atmospheric pressure and in such case a vent pipe, indicated by the dotted line 37, provided with a valve 38, may be connected to the pipe 30, as shown. When this is used the valve 45 38, which is normally closed, is opened and the valve 33 is closed to render the vacuum pump 31 inoperative, the gases from the tank 18 in this case passing out through the vent pipe 37.

I also contemplate that corrosive or chemically active de-oxidizing or de-activating materials may be used for the purpose of expediting the process and also, more particularly, for economically and effectively 55 removing the remaining dissolved oxygen and other free corrosive gases from the liquid after it has been subjected to the mechanical agitation process. This supplementary chemical provision for the de-oxidation 60 of the liquid is especially useful where the volume of the liquid passing through the de-activator is large for a given time.

It will be obvious that my invention is 65 adapted and useful for many purposes in

addition to that described and shown in connection with the water supply of buildings, among which may be mentioned the making of "artificial" ice, in which the formation of "cores" and "opaqueness" is avoided when the water is treated in accordance with this invention before freezing. When used for this purpose the advantage of being able to deliver the water at a comparatively low temperature will be apparent.

As many changes could be made in the above construction and arrangement and many apparently widely different embodiments of my invention designed without departing from the scope of the appended claims, I intend that all matter contained in the above description or shown in the accompanying drawings shall be interpreted as illustrative merely of an operative embodiment of my invention and not in a limiting sense.

What I claim is:

1. A system for rendering liquids non-corrosive, which comprises a de-aerating tank provided with means for agitating and separating the liquid supplied thereto into small particles, automatically regulated heating means adapted to heat the liquid to and maintain the same at a temperature a few degrees below the boiling point corresponding to the pressure in said tank, means for regulating the pressure in said tank, and means for drawing off the liquid from said tank after agitation.

2. A system for rendering liquids non-corrosive, which comprises a de-aerating tank provided with means for agitating and separating the liquid into small particles, automatically regulated heating means adapted to heat the liquid to a temperature a few degrees below the boiling point corresponding to the pressure in said tank, automatically controlled means for regulating the pressure in said tank, and means for drawing off the liquid from said tank after agitation.

3. A system for rendering liquids non-corrosive, which comprises a de-aerating tank provided with means for agitating and separating the liquid supplied thereto into small particles, automatically controlled means for producing a partial vacuum in said tank, means for heating the liquid before entering said tank to a temperature lower than the boiling point corresponding to the pressure to which it is subjected in said tank, and means for drawing off the liquid from said tank after agitation.

4. A system for rendering liquids non-corrosive, which comprises a de-aerating tank provided with means for agitating and separating the liquid supplied thereto into small particles, means for producing a partial vacuum in said tank, automatically

controlled means for heating the liquid before entering said tank to a predetermined constant temperature lower than the boiling point corresponding to the pressure to which it is subjected in said tank, and means for drawing off the liquid from said tank after agitation.

5. A system for rendering liquids non-corrosive, which comprises a deaerating tank provided with means for agitating and separating the liquid supplied thereto into small particles, automatically controlled means for producing a partial vacuum in

said tank, automatically controlled means for heating the liquid before entering said tank to a predetermined constant temperature lower than the boiling point corresponding to the pressure to which it is subjected in said tank, and means for drawing off the liquid from said tank after agitation.

In testimony whereof, I, the said JOSEPH F. MUSSELMAN, have signed my name to this specification, this 10th day of March, 1920.

JOSEPH F. MUSSELMAN.
